CLAIM

The ornamental design for a storage panel for ski boots or the like, as shown and described.

DESCRIPTION

FIG. 1 is a perspective view of a storage panel for ski boots or the like showing my new design:

FIG. 2 is a front elevational view thereof with the ski boots and supports therefore shown in broken lines for illustrative purposes only:

FIG. 3 is a top plan view thereof:

FIG. 4 is a bottom plan view thereof:

FIG. 5 is a side elevational view thereof, taken from the right of FIG. 2:

And FIG. 6 is a side elevational view thereof, taken from the left of FIG. 2, shown broken away for ease of illustration.
